UNITED STATES PATENT OFFICE.

EDMOND A. WARREN, OF BROOKLYN, NEW YORK.

INK-TABLE FOR PRINTING-MACHINES.

SPECIFICATION forming part of Letters Patent No. 330,533, dated November 17, 1885.

Application filed May 14, 1884. Serial No. 131,447. (No model.)

To all whom it may concern:

Be it known that I, EDMOND A. WARREN, a citizen of the United States, residing in the city of Brooklyn, in the county of Kings and State of New York, have invented a new and useful Improvement in Ink-Tables for Printing-Machines, of which the following is a specification, reference being had to the accompanying drawing, forming part of this 10 specification.

This invention relates to ink-tables the surfaces of which comprise the faces of two rotary disks arranged side by side.

The object of this invention is to simplify 15 such tables and the mechanism for operating them; and to this end the invention consists in the combination of two such disks, having on their peripheries matching projections, whereby they are caused to so engage with 20 each other as to form of themselves a complete table capable of distributing the ink along the whole length of a roller without interruption, and that rotary motion imparted to one will be transmitted directly through it 25 to the other.

The drawing represents a face view of an 30 ink-table constructed according to my invention, and a longitudinal view of a pair of ink-rollers applied to said table.

A A' are the two circular disks, having in 35 their peripheries projections *a a* and recesses *b b*, which match in such a manner that the projections on the one engage with the recesses in the other, like the teeth of spur-gear wheels. These disks have their faces perfectly 40 flat and arranged in the same plane, so that they constitute sections of one ink-table. They are supported and maintained in proper relation and engagement with each other by being fitted with or to central axles or journals (indicated by the dotted circles *c c*,) supported in the printing machine or press in any 45 suitable manner, according to the form or construction of the said machine or press. To one of the said disks a rotary motion is given by a ratchet and pawl or other suitable means—such as are commonly employed or suitable for giving motion to a rotary ink-table—and the other disk receives motion from the first one through the projections and recesses *a b* in their peripheries.

B B are the ink-rollers, of which there may be any suitable number, but of which two are shown, their length being sufficient for them

to reach across both disks A A'. These rollers 55 may be supported and operated in the same manner as in any of the printing-presses in which a rotary ink-table is used. They are represented as having bearings in two yokes, *e e*, fitted loosely to a shaft, *d*, which is 60 firmly secured in two arms, C C, which have a reciprocating motion imparted to them by any suitable mechanism that will cause the rollers to move back and forth across the table. As such mechanism constitutes no part 65 of this invention, and is well understood, I have not thought it necessary to represent it, but will mention that the mechanism described for the purpose in my application No. 131,446, filed May 14, 1884, for Letters Patent for improvements in numbering-machines, is suitable.

This improved ink-table is applicable to various kinds of printing machines and presses. It occupies much less room than a rotary ink-table of the same width consisting of a single disk, while it obtains at least as perfect if not a more perfect distribution of the ink, the ink being distributed by the rollers from one disk to the other by the rollers passing over the intermeshing projections *a a*. The said projections on each disk, entering the corresponding recesses or spaces in the other one, produce such a continuity 75 or sequence of contact between the ink-rollers and the disks that the ink is distributed 80 without interruption along the whole length of the roller, and hence the two disks constitute in themselves a complete table, instead of being simply adjuncts of another table, like the disks shown in expired Letters 85 Patent No. 62,032; and, moreover, the said projections cause one disk to transmit rotary motion directly to the other without requiring any other gearing between them or a 90 separate driving mechanism for each.

What I claim as my invention, and desire 95 to secure by Letters Patent, is—

An ink-table for a printing machine or press, consisting of a combination of two rotary disks arranged side by side and having 100 in their peripheries matching projections and recesses which engage with each other, substantially as herein described.

EDMOND A. WARREN.
